(57) **CLAIM**

The ornamental design for a light therapy device as shown and described.

DESCRIPTION

1. Light therapy device

1.1 : Perspective

1.2 : Front

1.3 : Back

1.4 : Left

1.5 : Right

1.6 : Top

1.7 : Bottom

The light therapy device is characterized by a rectangular box-shaped base having a bottom joined to four sides; a back side rises higher off the base than the front side, as shown by FIG. 1.1, FIG. 1.4, and FIG. 1.5; the right side displays a drawer cutout as shown by FIG. 1.1 and FIG. 1.5; the sides of the base connect to a curvilinear top formed from a translucent or transparent material to allow visible and non-visible light illuminating an interior aspect of the top from a light source positioned within the drawer inside the base to pass through the top; the uppermost aspect of the top presents a bowed surface when viewed from the front or the back as a neck rest for a user, shown by FIG. 1.2 and FIG. 1.3.

The broken lines shown in the drawings are for the purpose of illustrating portions of the article that form no part of the claimed design.
